(57) **CLAIM**

The ornamental design for a chopping board, as shown and described.

DESCRIPTION

FIG. 1 is a front, end view of the FIG. 4 embodiment of the chopping board of FIG. 2;

FIG. 2 is a top view of a chopping board of the present design;

FIG. 3 is a side view of the chopping board of FIG. 2;

FIG. 4 is a bottom perspective view of the chopping board of FIG. 2; and,

FIG. 5 is a top perspective view of the chopping board of FIG. 2.

The shading in the figures show contour, not surface ornamentation, and form no part of the claimed design.

The dashed lines shown in the figures are for illustration only and form no part of the claimed design.
